INTERNAL-COMBUSTION ENGINE.

1,305,577.

Specification of Letters Patent. Patented June 3, 1919.

Application filed February 5, 1912. Serial No. 675,518.

To all whom it may concern:

Be it known that I, MERL R. WOLFARD, a citizen of the United States, residing at Cambridge, in the county of Middlesex and State of Massachusetts, have invented new and useful Improvements in Internal-Combustion Engines, of which the following is a specification.

This invention relates to improvements in internal combustion engines, being here illustrated more particularly as it may be applied to a two cycle engine using heavy oil fuel, although the invention or suitable parts of it may be applied to various types of engines, and to engines working on various cycles, and with various kinds of fuel.

It is the object of the invention to improve on preceding engines by providing an increase of capacity in engines of given size or weight; an increase of efficiency, both thermodynamic and mechanical; a reduction of number of valves and moving parts; a general simplification of the mechanism as a whole; and the elimination of certain troublesome mechanism, particularly that for producing the high pressure fuel-injecting blast, which has hitherto been thought necessary in some types of engines. It is also the purpose to attain the other advantages which result from the improvements herein disclosed, and to cover by Letters Patent such features or combinations as are novel and patentable.

In engines of the Diesel type, which represent the highest efficiency heretofore attained, in practice, it has been necessary to force the charge of fuel oil into a body of air, so greatly compressed that it has a temperature high enough to ignite the oil. The oil has to be comminuted and distributed in this body of air, in order to get complete combustion quickly. This has hitherto been attempted by using an auxiliary supply of air of yet higher pressure, but at lower temperature, to blow in the oil, in the form of spray.

It is the inventor's belief that the attenuated character of the clearance space in engines as heretofore constructed, has been an important cause of the universal failure, in practice, to attain the efficiency which is theoretically possible. At the inner end of stroke, the air is distributed in a wide thin

layer over the end of the piston. The fuel which enters earlier consumes the air nearest the place of entrance. The fuel which enters later then finds itself surrounded by the combustion or products of the combustion of the earlier fuel; and it cannot burn until the piston has moved out far enough for this later fuel to become mixed with the remote air. This results in retarded combustion or "after-burning".

In an engine embodying the present invention the clearance space, or what may for present purposes be called the clearance space, is so located at the beginning of fuel admission, and is so changed in its location while the admission of fuel continues, that the air that has been impounded and compressed, ready for the next combustion, rushes past the fuel inlet valve as the fuel is entering. Thus each particle of oil, as it enters, finds at once an abundance of air for its combustion. This rush of air may of itself tend to cause sub-division of the oil into minute particles, somewhat as has the higher-pressure blast of air injected heretofore; but the insertion and spraying of fuel is effected by simple mechanical means without any such higher-pressure blast.

This is accomplished by providing two cylinders, one having a piston lagging a suitable distance behind the piston in the other, for example, in certain types of engines, 30° to 50° , the distance varying according to dimensions and adjustment of the engine. Each piston runs to the very head of its cylinder. The head ends of the two cylinders are connected by a suitable open passage, in which are located the oil inlet port and, if desired, an ignition device. As here illustrated one cylinder is considerably larger than the other, but this relation of sizes is not necessary. Each cylinder has ports which are uncovered by its piston in the ordinary way at the end of stroke, the ports of one being connected to a supply of air, impelled by a slight pressure, and the ports in the other cylinder being connected to exhaust. This air rushes through the cylinder it first enters, through the passage into the other cylinder, and thence to the exhaust ports therein, with good scavenging effect. The inward strokes of the pistons, which then ensue, close the ports, both inlet and

exhaust, in an improved manner or relation as hereinafter described so as to obtain a complete scavenging and a start from atmospheric pressure; and compress the air thus impounded in the two cylinders until, at the inner end of stroke of the leading piston, the air is under high pressure, ready for the admission and combustion of the next charge of fuel, and is contained mainly in the cylinder which has the lagging piston, and in the passage. As the leading piston then starts outward, the lagging piston being still in motion inward, the location of the clearance space changes. Air rushes from the passage toward the leading piston, passing the fuel admission valve which, at that moment, begins to inject oil. The air takes up the oil in particles and carries it burning into the leading cylinder, where expansion occurs. This mixing of oil and air may be expedited, if desired, by the mechanical distributor of oil hereinafter described. The flow from the other cylinder continues until the lagging piston reaches its inner end of stroke. The admission of fuel may continue as long as desired, the fuel burning as it enters. After the lagging piston starts outward, expansion occurs in both cylinders until the exhaust is opened in the one cylinder, closely followed by the inlet of air to the other. As illustrated, the lagging piston and the exhaust ports are in the smaller cylinder.

The movements of the two pistons relative to each other, and the consequent times of opening and closing the ports, are also features of novelty. The cylinder which has the exhaust ports is illustrated as having approximately one fourth of the volume of the other cylinder. It is arranged with its axis offset from the diametrical line of the crank circle; its piston rod is relatively short; and its ports are relatively longer than those in the other cylinder. The result is that, although the cranks remain always at a fixed angle apart, the relative positions of their pistons vary. The smaller, having completed its inward stroke at a certain interval of time after the larger, moves outward with greater speed than does the leading piston, and opens the exhaust ports before the larger piston opens the air inlet ports. And its ensuing inward stroke is slower than the inward stroke of the larger piston, particularly at the beginning, thus holding the exhaust open for a period after the air inlet ports have been closed. During this delay the air which has entered the inlet ports in the larger cylinder completely drives out any products of combustion not expelled by the first rush, and leaves the contents of the two cylinders at approximately atmospheric pressure at the beginning of compression.

The construction described gives a period of combustion at every revolution; expan-

sion in two cylinders; complete exhaust and scavenging; a suitable compression of pure air for the next combustion; and access of sufficient air to every particle of fuel at practically the instant of such particle's entrance to the chamber with resultant continuous and complete combustion. This also allows the use of a hot combustion chamber which further facilitates instantaneous and complete combustion as, for example, by vaporizing and igniting the oil introduced, besides adding marked thermal advantages which cannot be obtained where valves and water-cooled cages form a large part of the inclosing walls of the combustion chamber. Any desired ignition system may be used.

No high-pressure air injection is required to insert the fuel. No mechanically operated valve is required, either for admission, or for transfer of air, or for scavenging, or for exhaust of the products of combustion. The air used for scavenging, and for the combustion, enters under small pressure such as may be obtained, for example, by crank-case compression, or by a differential piston.

The thermodynamic efficiency theoretically and practically obtainable is greatly increased by the extended expansion secured through the novel arrangement of two pistons and the ports, without increasing the number of mechanical parts over those otherwise necessary for mixing the charge.

The accompanying drawings which are somewhat diagrammatic, illustrate an embodiment of the invention, various constructional details and arrangements being omitted:

Figure 1 is a side elevation in central section through the two cylinders;

Fig. 2 is an end elevation in section on the line 2-2 of Fig. 1;

Fig. 3 is a plan in section on the line 3-3 of Fig. 1;

Fig. 4 is an end elevation of a detail enlarged in section on the line 4-4 of Fig. 3;

Fig. 5 is an elevation in section showing an alternative structure of a detail, enlarged;

Fig. 5a is a side elevation of the same;

Figs. 6a-6f are diagrams of simultaneous piston positions; and

Fig. 7 is a diagram of compression and expansion of the working fluid.

Referring to the drawings, 10 represents the larger cylinder, 11 the piston therein, 12 the air inlet ports therein and 13 the crank shaft to which the piston is connected. 20 represents the smaller cylinder, 21 the piston therein and 22 the exhaust ports therein. The crank of the larger piston is represented as inclosed in a case 14 from which a passage 15 leads to the inlet ports 12. A passage 30 connects the head ends of the two cylinders. In this passage is an ignition device 31 and an admission port 32, for oil or other fuel, 120

each of which may be of any suitable type. The drawings also indicate a pipe 33 leading from a pump 34 which may be conveniently located, for supply of fuel, the pump being driven by a cam 35 on the main shaft 13, by which oil is injected into passage 30 at predetermined times.

The ignition device 31, as illustrated, consists of two nickel steel points between which an electric arc is formed. One point 31' may be merely a knob on the under side of the passage 30, the other 31'' being adjustable toward and from the knob 31' by means of a screw 36, and one or both of these being suitably insulated from the engine casing, as at 37. The conductors leading to these two terminals are marked 38, 38'. The ignition device 31 is preferably arranged with its arc in a recess 39 in the side wall of the passage 30, so that it is not in the direct line of flow through the passage, yet is within the line of discharge from the fuel injecting port 32, (Fig. 3). A special ignition device such as this is not required if the compression of air in the cylinders and passage 30 be high enough, as in engines of the Diesel type, because the air temperature will ignite the fuel. In engines working on lower compression of air the ignition device may generally be cut out of action after the engine has been running a few minutes, ignition being then caused by the high temperature retained in the passage 30, this being the system herein referred to as ignition by hot combustion chamber. It is only when the engine is starting, or is running on very low pressures, that any special ignition device will be needed.

The fuel admission port 32 is a discharge orifice, exaggerated in size in the drawing, for clearness, leading from a hollow rotating hollow plug 40 which projects into the passage 30, being partly embedded in the side walls thereof opposite the ignition device, as illustrated in Fig. 1. The interior of this plug 40 is filled with fuel from the supply pipe 33 through a chamber 42 in the stationary block 43 and an opening 41 in the rotating plug 40. The plug is seated in this block on ground bearings 44, 44, which prevent leakage and hold its upper end clear from the surrounding hot walls. It is rotated at a suitable speed by gears 45. In an engine constructed as illustrated it is desirable to have the discharge nozzle 32 move while the fuel is being injected, so that, starting with its initial direction of discharge toward the ignition device and the entrance to the large cylinder 10, it shall sweep toward the other end of the passage 30 and the entrance from the small cylinder 20. The connection to the main shaft 13 should be arranged to produce the desired amount of rotation of the plug 40 during the period in which admission of the fuel is to occur. The

rotation at other times is of no consequence, because flow of fuel occurs only when the pump 34 is actuated by the cam 35. Consequently there may be one or more complete rotations of the plug between inflow periods, 70 without escape of oil. The movement of the nozzle 32 while fuel is being introduced distributes the fuel through the air which is ready in the passage 30 and in the head end of the cylinder 20. The orifice may, if desired, be annular as at 32' in Fig. 5, where an interior spring hook tends to hold the valve in closed position on the orifice. When very small quantities of fluid pass through a valve like this, the distribution is 75 made more certain by concentrating the flow at fixed points in the circumference, for which grooves 32'' are illustrated, seen best in Fig. 5^a where the valve has been removed. These grooves extend through the valve-stem-guide, which is integral with the valve seat. The valve stem and guide may be slightly tapering. Then the stem can be ground to a perfect fit at the same time that the valve is ground to its seat. 90

If preferred, the nozzle 32 may be held stationary, pointing toward the ignition device, in which case the fuel that it delivers will be taken up as the air rushes past it toward the outgoing piston in the large cylinder 10. The described movement, in which the nozzle is swung gradually toward the direction from which the air is moving, makes the distribution more rapid, because the more remote air receives its load of fuel 100 before reaching the nozzle.

In the type of engine illustrated in Fig. 1 the pistons travel close to the cylinder heads, expelling all the contents thereof into that space which is in the passage 30, which remains fixed in location, and is here referred to as fixed clearance space, and that space which is in the cylinder 20 which may be considered as shifting into the other cylinder 10, as the lagging piston 21 advances inward, and the leading piston 11 moves outward. The fixed clearance space may be a large or small proportion of the whole, according to the design of the engine, the size of passage 30 and the degree of lag of the piston 21. If 105 the fixed clearance space be relatively small, the rate of injection of fuel should bear some proper relation to the rate at which air is displaced from the clearance in cylinder 20 and driven into the clearance which is 110 formed in cylinder 10 as its piston moves out, in order to secure good mixing and also to prevent the pressure resulting from combustion from becoming too great before expansion occurs. If, on the contrary, the 115 clearance space 30 be relatively large, it is more capable of holding the air displaced from cylinder 20; and the piston 21 may then be set so that it lags less behind the other piston. This makes an engine of some- 120, 125, 130,

what greater capacity of output. Also, the walls of the passage 30, where it is of larger cross-section, absorb less heat during combustion and are cooled less during scavenging.

Any suitable means may be employed for preventing excessive heating of the cylinder walls, piston, etc., a water jacket being illustrated.

- 10 Heat may be conserved by making a lining 46 of white iron crucible steel or other tough and tenacious material chosen primarily for its strength and durability, without regard to its heat absorbing or heat conducting qualities and, suitably insulated from the walls, as by a thin layer of asbestos 47. Warping of this lining, by unequal expansion caused by the great heat, may be prevented by making one or more saw-cuts 48, which in the case of the cylinder or piston plate may be arranged radially, as illustrated in Fig. 3. The asbestos which would be thus exposed may be guarded from disintegration by a thin intervening plate of metal 49. The greatest changes of temperature then occur in this lining, but as it is only loosely attached, as by a central bolt 50, as illustrated, (Fig. 1), serious stresses are not transmitted to the cylinder casing.
- 30 Enough heat is transmitted, however, to prevent overheating of the said lining. This relieves the outer wall from much of the distortion due to temperatures, and makes the gradient of temperatures through the outer side wall reasonably constant. This lining serves as a screen for heat inside the chamber. The heat retained by this screen is in the ordinary type of engine carried away by the water jacket. Over and above this valuable conserving of heat in one cycle for the next, this hot screen or lining has two other important functions: it is an ideal vaporizer for liquid fuels; and it is an ideal igniter and combustion chamber. No particle of oil can strike the walls anywhere without being instantly vaporized and completely burned, thus eliminating after-burning. These advantages have been claimed for porcelain or similar linings, but such materials crack and
- 50 are not practicable.

The arrangement of the piston and ports for air inlet and for exhaust in the two working cylinders is another feature of the invention. The lagging of one piston on the inward stroke, produces the arrangement and shifting of clearance space, with quick mixing of air and fuel, above described; but this lagging piston moves faster on the outward stroke, gaining on the leading piston, so that it opens the exhaust ports as soon as, or preferably just a little before, the leading piston opens the air inlet ports. To accomplish this in the simple type of engine illustrated, without introducing a secondary crank shaft as may be preferred in multi-

cylinder engines, to drive the small and lagging pistons, the lagging piston 21 is connected by a rather short rod 21' to a crank 23' hung on the end of the main shaft 13; and the cylinder 20 is offset a little from the plane of the axes of the main shaft 13 and the larger cylinder, which axes intersect in the usual way. The distance which the smaller cylinder is thus offset, and the length of the rod connecting its piston to the crank, 70 may vary according to circumstances, but it is believed that in the best practice the former will usually be equal to between one-third and two-thirds of the length of the crank 23', and the latter be from two to three 75 times the length of said crank. Owing to the confinement of the piston end of the connecting rod 21' to a line unsymmetrical with respect to the crank circle the two dead centers of that rod are not symmetrically disposed, in the crank circle. In the diagrams, Fig. 6^a the location of these two points is indicated by the letters *c'* and *c''* respectively. Consequently, if the crank 13 rotate at uniform speed the piston 21 will make its 80 outward stroke somewhat more rapidly than its inward.

The relation and the operation of these various parts to each other will be here explained by the use of an illustrative example. For this purpose the following proportions of dimensions are assumed: Length of crank of larger or leading piston seven and one-half inches, giving stroke of fifteen inches; the cylinder having a diameter of 100 ten inches, and air inlet ports extending three-fourths of an inch above the lowest point of piston travel. Length of crank of small or lagging piston five inches, giving a piston stroke of approximately ten and one-half inches; this cylinder having a diameter of six inches, exhaust ports extending two inches above the lowest point of piston travel, and being set with its axis parallel to that of the other and three inches distant from the plane of that other cylinder and the main shaft; the rod connecting this piston to its crank 23' being twelve and one-half inches in length; and the crank 23' being set on the same shaft with the crank 115 13' but at an angle of 45° lag with respect thereto. It will be understood that these dimensions are purely for illustration, and may be varied in practice, not only by increasing or decreasing them, but also by changing their proportions to each other within reasonable limits in accordance with the principles of the invention. Figs. 6^a-6^c illustrate diagrammatically the relations of the parts to each other at successive critical points in an 120 engine having the proportions stated. These indicate the two cranks, 13' and 23', turning about the common axis 13, and connected by rods 11' and 21' respectively to the pistons 11 and 21 in cylinders 10 and 20. The 125 130

diagrams show graphically the location and extent of the ports, 12 and 22, and, by double lines, the portions of the crank circle in each case corresponding thereto. The relative positions of the pistons 11 and 21 at the beginning of compression are indicated in Fig. 6^a. The leading piston 11 has then about half completed its inward stroke, when the lagging piston 21 is closing the exhaust ports 22. In Fig. 6^b the leading piston is at its inward end of stroke, the stroke of the piston 21 being still incomplete. Compression is completed; and fuel injection is about to begin, to continue while the lagging piston completes its stroke and forces air past the fuel inlet. In Fig. 6^c the piston 21 is at its inward end of stroke, and the leading piston 11 is well under way on its outward stroke. In Fig. 6^d expansion has been completed; both pistons are near their outward end of stroke, the piston 21 having reached the exhaust ports, which is followed an instant later, Fig. 6^e, by the piston 11 reaching air inlet ports. A period of retardation of the piston 21 then follows while it is passing its dead center, and while its connecting rod is straightening into line with the axis of its cylinder until the position where this piston closes the exhaust ports. In Fig. 6^f the leading piston has been to its outward limit, and, on its return, is closing the air inlet ports, while the crank of piston 21 has barely passed its outward dead center. The air inlet then remains closed and the exhaust remains open till the position shown in Fig. 6^a is reached, after which the compression stroke is relatively rapid from the position of Fig. 6^a to that of Fig. 6^b.

Beginning with the position indicated in Fig. 6^a, which is the close of exhaust, pure air is compressed in both cylinders starting at about atmospheric pressure. The maximum compression is reached approximately at the position indicated in Fig. 6^b, at which time the piston 11 begins to move outward, creating a space toward which the compressed air is driven, past the fuel inlet, by the still advancing piston 21, till this lagging piston 21 reaches its inward limit as indicated in Fig. 6^c, after which expansion occurs in both cylinders. Upon the opening of exhaust, which it will be observed is very close to the end of stroke of both pistons, although the exhaust did not close till the inward stroke of the larger piston was about half completed, contents of both cylinders flow out, impelled by expansion and by the inrush of air under slight compression through the inlet ports. After the inlet ports are closed, Fig. 6^f, the exhaust ports continue open. This enables the pressure in the cylinders to fall to atmospheric pressure, or to whatever level of pressure exists outside of exhaust ports, in case a condenser or suction device be employed. The steady ad-

vance inward of the large piston pushes the recently admitted air ahead of it, which in turn pushes ahead of itself any products of combustion, out through the exhaust ports, so that when the exhaust ports finally close, 70 Fig. 6^e, both cylinders contain only pure air. This is an advantage over previous engines working by crank case compression, because it is not possible by the method of compression to transfer to the working cylinder 75 its full volume of pure air, owing to the differences of pressure needed to effect the transfer of air from the atmosphere into the crank case and from the crank case into the cylinder; and the fractional volume of 80 air thus introduced becomes mixed with the other contents of the cylinder; whereas in the present invention the fractional volume of air does not become mixed, but remains while the other contents are expelled on the 85 first portion of the inward stroke.

This purity of air results in a more rapid and complete combustion of the charge than heretofore customary in two-cycle engines, thus adding both to the efficiency and to the 90 capacity of the engine. Indeed the charge of air for combustion will be even purer than in the ordinary four-cycle engine, in which the inert gases are never expelled from the clearance and mix with the charge 95 during the suction stroke.

The described arrangement of inlet and exhaust closing, and of exhaust opening, makes two other important additions to the economy heretofore attained in engines having 100 piston-operated valves, which will be explained by reference to the theoretical diagram, Fig. 7.

In the diagram, 2-3 represent the compression line of a working fluid; 3-4 its 105 expansion at constant pressure with addition of heat during combustion; and 4-5 its adiabatic expansion thereafter, 1-2 being the line of atmospheric pressure. The distance 1-2 represents the volume or displacement of a certain weight or quantity of air at atmospheric pressure. If this same weight were at two pounds pressure the distance 1-8 would indicate its displacement. 110 In an engine beginning to compress the assumed weight at two pounds would therefore close its exhaust valves at the point 8; and the length of piston stroke would be substantially the distance 8-1 according to customary practice in engines having piston operated valves. On the outward stroke the exhaust valve would open at the same distance of piston movement, indicated at 9. The work done would be indicated by the area 8-3-4-9. In an engine embodying the invention, and holding the same weight of fluid at atmospheric pressure at the beginning of compression, the exhaust valve would close at 2; the length of stroke 125 would be 2-1; and if the exhaust were to 130

open on the outward stroke at the same piston position at which it closed, indicated by the point 5, the work done would be shown by area 2—3—4—5. Thus the engine of the invention would work at greater thermodynamic efficiency than an engine expanding the same quantity of fluid only to the point 9, the addition being indicated by area 9—5—2—8. This gain would be due to the arrangement by which compression begins at atmospheric pressure.

However, the invention provides means by which the exhaust does not open on the outward stroke at the point last supposed, viz., at the same piston position at which it closed on the inward stroke. Its opening is delayed, and extended expansion is obtained, which, as is seen by comparing Figs. 6^a and 6^b, is equivalent to adding about 50% to what the displacement would be if the opening of exhaust were at the same point in the stroke of piston 11 as its closing on the inward stroke. The additional work thus obtained is represented in the card by 25 the area 5—6—7—2.

The percentage of economy thus gained varies with the initial pressure and other circumstances; but a general idea of the effect may be gained from the following table 30 of approximate figures showing the thermodynamic efficiency of a two-cycle engine of the Diesel type working at the various different pressures stated, where the first column represents absolute pressures in pounds 35 per square inch; the second, the theoretical thermodynamic efficiency of a two-cycle Diesel type engine, with compression beginning at two pounds above the atmosphere; the third, the percentage added thereto by 40 the total area 9—6—7—8 of Fig. 7 assuming the displacement on the expansion stroke to be 50% greater than on the compression stroke; and the fourth, the total theoretical thermodynamic efficiency of an engine embodying the invention and working perfectly in the manner indicated:

Initial pressure.	Efficiency.		
	Two-cycle Diesel.	Per cent. added.	Total.
176.6	29.5	40.3	41.4
277.	39.5	33.0	52.5
374.	46.3	21.3	56.1
562.	56.6	11.3	63.0

5 The engine of the invention is not necessarily operated on the high pressures which are an essential characteristic of the Diesel type, because ignition can be obtained by a 60 hot combustion chamber. The movement of gases is such that the combustion occurs mainly in the immediate vicinity of the combustion chamber; the larger portion of the hot products of combustion pass by that 65 chamber on their way to exhaust (when the

exhaust is from the smaller cylinder as illustrated); and only a small part of the cool, freshly admitted air passes by that chamber. Consequently the chamber stays at ignition temperature; a result to which the placing of the chamber 39 as a recess in the side of passage 30 contributes.

It should also be noted that the valves required in the engine of the invention are very simple, both in number and type. The 75 ports 12 and 22 of the cylinders are controlled automatically by the pistons. A simple fuel pump forces the oil past an automatic valve at the proper rate and time, this valve being so small and of such 80 simple construction that it gives no trouble in operation. The admission port for air to the crank case 14 may have a simple check valve 14' as illustrated, because pressure against it is never great. While this construction is illustrated in order not to complicate the drawings, other devices in common use might be substituted, such as an arrangement by which one of the pistons controls the admission port to the crank case. 90 So also the system of crank-case compression is suggested for the same reason, but obviously compression by the differential piston method might be substituted in the manner well known, and might indeed be 95 preferable.

If the engine operates on the Diesel principle, the invention enables a considerable advantage to be gained over other Diesel engines, because the necessity of providing an 100 outside high-pressure air mechanism to introduce and distribute the fuel in the combustion chamber is eliminated. The heat losses incidental to such outside work, and to cool valve surfaces in the combustion 105 chamber, and the mechanical troubles and deterioration in efficiency which, in practice, accompany such mechanism, are also eliminated.

The loss of heat and pressure heretofore 110 experienced by those who have compressed air outside of the working cylinder, according to other methods, as for example, the method of the Brayton engine, is wholly or largely saved, because air hot from the final 115 compression in one cylinder is delivered immediately into the closely adjacent other cylinder through a free passage, without valves. The free connection between the cylinders enables expansion to be carried to 120 a very low point, so that either the output of power per unit of weight, or the efficiency, or both, of an engine embodying this invention will be high, as compared with that of other engines of the same weight or size. 125 The completeness of the scavenging, and the fact that it includes the clearance space in its action enables these advantages to be utilized to the fullest degree in an engine of any given size. 130

I claim:—

1. An internal combustion engine including in combination two cylinders and means to admit air to them for the combustion; a passage continuously open between their head ends, sufficient in size for the main body of air to pass through it under normal operating conditions without material increase of pressure; pistons in the cylinders, connected together to move the main body of air through said passage at their inner end of stroke; means to inject the fuel charge directly into said main body of air at the inner end of stroke gradually while it is so being moved; and means whereby the fuel ignites and burns gradually during the continuance of its said injection into the main body of air.
2. An internal combustion engine including in combination two cylinders and means to admit air to them for the combustion; a passage continuously open between their head ends, sufficient in size for the main body of air to pass through it under normal operating conditions without material increase of pressure; pistons in the cylinders, connected together to move the main body of air through said passage at their inner end of stroke; a pipe holding a column of liquid fuel extending continuously to said passage; a pump acting on said fuel, injecting part thereof gradually into said passage while the main body of air is so being moved; and means whereby the fuel ignites and burns gradually during the continuance of its said injection into the main body of air.
3. An internal combustion engine including in combination two cylinders and means to admit air to them for the combustion; a combustion chamber connecting their head ends sufficient in cross-sectional area for the main body of gases to pass through it under normal operating conditions without material increase of pressure; a piston in one cylinder having approximately no clearance therein; there being clearance for it in said chamber; a piston in the other cylinder connected to the first piston in such relation as to reach its inner end of stroke after the first mentioned piston has reached its inner end of stroke and is moving outward; and means gradually to inject fuel across said chamber, while the main body of air which is to support the combustion thereof is being pushed past the point of fuel injection by the second mentioned piston.
4. In an internal combustion engine, the combination of a working cylinder, and a piston therein traveling to the head of the cylinder approximately without clearance therein; another cylinder connected therewith, and a piston therein; there being a chamber affording space outside of said
- working cylinder coöperating with space in the second cylinder to provide capacity between the two pistons for holding the main body of air for supporting combustion; means to inject fuel gradually into said main body of air at a place near the junction of said chamber with said working cylinder; whereby on the outward stroke of the piston in said working cylinder said main body of air flows gradually past said place where fuel is being injected while it is being injected; and means whereby the main combustion occurs immediately upon and progressively with said injection of fuel.
5. In an internal combustion engine the combination of a working cylinder and a piston therein traveling to its head approximately without clearance therein; means inclosing space outside of said working cylinder for the main body of air compressed by said piston for supporting the combustion, said space having a connection of sufficient size for gases under normal operating conditions to flow from it to the said working cylinder without any material increase of pressure, due to construction of passage; means to inject fuel gradually into said space at a place near the entrance therefrom to said working cylinder, and displacing means adapted and organized to force the main body of air past the place of fuel injection during said fuel injection at and after said piston's inner end of stroke.
6. In an internal combustion engine the combination of a working cylinder and a piston therein traveling to its head approximately without clearance therein; means inclosing space outside of said working cylinder for the main body of air compressed by said piston for supporting the combustion, said space having a connection of sufficient size for gases under normal operating conditions to flow from it to the said working cylinder without any material increase of pressure due to constriction of passage; means to inject fuel gradually into said space at a place near the entrance therefrom to said working cylinder; displacing means adapted and organized to force the main body of air past the place of fuel injection during said fuel injection at and after said piston's inner end of stroke; and means whereby ignition occurs approximately at the beginning of said injection of fuel.
7. In an internal combustion engine the combination of two connected cylinders and positively-acting pistons therein, ending their inward strokes at different times, there being free connection between the head ends of said cylinders, continuously open to the extreme end of stroke in each cylinder and sufficient in size for passage of the main body of cylinder contents in either direction under normal operating conditions without material increase of pressure; and means

whereby the main combustion begins immediately upon entrance of fuel and continues progressively with injection of fuel into said main body of air.

- 5 8. In an internal combustion engine the combination of two connected cylinders and positively-acting piston therein, ending their inward strokes at different times, there being free connection between the head ends of 70 said cylinders, continuously open to the extreme end of stroke in each cylinder and sufficient in size for passage of the main body of cylinder contents in either direction under normal operating conditions without 75 material increase of pressure; and means to introduce fuel gradually while the pistons are near their inward limit of stroke directly into said continuously open passage and to cause its combustion therein progressively with such introduction.

9. In an internal combustion engine the combination of a cylinder, a working piston therein compressing air on inward stroke, there being space constituting clearance outside the cylinder to receive such compressed air, said space having a connection of sufficient size for gases under normal operating conditions to flow from it to the said working cylinder without any material increase of pressure due to constriction of 80 passage; a fuel inlet to said space and means whereby fuel is injected thereinto gradually, immediately after each inward stroke; another cylinder, connected with said first 85 cylinder through said space, and a piston in the second cylinder, connected with the first piston and displacing the clearance toward the first cylinder during fuel injection; the whole organized and arranged so that the 90 said displacement of clearance operates substantially without producing excess pressure above the normal pressures of the main compression and combustion and so that the fuel burns progressively as it is injected.

45 10. In an internal combustion engine the combination of a cylinder, a working piston therein compressing air on inward stroke; another cylinder connected with the first and affording clearance for the air compressed therein; a piston, in the second cylinder, connected with the first piston, and displacing the clearance toward the first cylinder; and a fuel inlet and means whereby fuel is injected into said clearance gradually, immediately after each inward stroke of the working piston and during said displacement of clearance; the whole organized and arranged so that the said displacement of clearance operates substantially without 105 producing excess pressure above the normal pressures of the main compression and combustion and so that the fuel burns progressively as it is injected.

60 11. In an internal combustion engine the combination of two cylinders, a passage con-

necting them; a piston in each cylinder; air ports in one supplying both cylinders; exhaust ports in the other, relieving both cylinders; said passage being a combustion chamber; one wall thereof having a recess 70 forming a hot ignition spot adjacent to but out of the direct currents flowing through said passage to and from said ports.

12. In an internal combustion engine, in combination, a cylinder and chamber connected therewith by a continuously open passage having a cross sectional area less than that of said cylinder, but sufficient for the main body of gases to pass through it under normal operating conditions without 80 any material increase of pressure, a piston in the cylinder; means to inject fuel gradually at the time of combustion and displacing means acting concurrently with the injecting means, the two co-operating to distribute said fuel progressively through the 85 main body of engine contents.

13. In an internal combustion engine the combination of two connected cylinders, one being larger than the other, connected pistons therein; a hot ignition spot in the passage connecting the cylinders; air ports for both cylinders in the larger; exhaust ports for both cylinders in the smaller; whereby a maximum of hot gases and a minimum of 90 cool air flow past the ignition spot at end of outward stroke; and means to inject fuel for immediate combustion at the end of inward stroke.

14. In an internal combustion engine the combination of two connected cylinders, pistons therein having cranks connected together, one lagging behind the other; the cylinder of the lagging piston being offset from the plane passing through the axis of 105 its crank parallel to its own axis, exhaust ports in the offset cylinder, air ports in the other cylinder relatively shorter than the exhaust ports; and means to inject fuel at the inner end of stroke.

15. The combination, in an internal combustion engine, of two cylinders, a passage connecting them, air ports in one, exhaust ports in the other, a piston in each cylinder controlling its ports, and means whereby the 115 piston-controlled exhaust ports remain open on inward stroke until a considerable proportion of the combined piston displacement has occurred, and remain closed on the outward stroke until nearly the whole combined 120 displacement has occurred.

16. In an internal combustion engine the combination of two connected cylinders; connected pistons in them, one lagging behind and being smaller than the other and offset from the plane passing through the axis of its crank shaft parallel to its own axis; a relatively short rod connecting its piston and crank, whereby said piston is 125 speedier than the other on the out-stroke and 130

slower on the in-stroke; ports for air inlets controlled by the larger piston; and ports for exhaust, opened by the smaller piston as soon as the air ports are closed by it after them.

17. In an internal combustion engine, in combination, a cylinder and a chamber connected therewith by a continuously open passage having a cross sectional area less than that of said cylinder, but sufficient for the main body of gases to pass through it under normal operating conditions without any material increase of pressure, a piston in

the cylinder; means to project a spray of liquid fuel into the chamber at the time of combustion; and displacing means, acting simultaneously with the projecting means whereby the said fuel spray is directed to different parts of the main body of engine contents successively.

Signed by me at Boston, Mass., this 30th day of January, 1912.

MERL R. WOLFARD.
